CLAIM

The ornamental design for a display screen with a patent family graphical user interface, substantially as shown and described.

DESCRIPTION

The FIGURE is a front view of a display screen with a patent family graphical user interface showing our new design. The ornamental design being claimed is shown in solid lines in the drawings. The outer broken lines, with large line segments and large spacing, illustrate the display monitor. The small diagonal broken lines contained within the outermost solid rectangular line illustrates environmental features. All broken lines form no part of the claimed design.
